US00D583349S

(12) **United States Design Patent**
Lee et al.

(10) **Patent No.:** US D583,349 S
(45) **Date of Patent:** ** Dec. 23, 2008

(54) **COMMUNICATION DEVICE**

(75) Inventors: **Sang Soo Lee**, Gyeonggi-do (KR); **Cho Bum Gyu**, Seoul (KR); **Soongul (Andrew) Kwon**, Seoul (KR)

(73) Assignee: **Motorola, Inc.**, Schaumburg, IL (US)

(**) Term: **14 Years**

(21) Appl. No.: **29/303,495**

(22) Filed: **Feb. 11, 2008**
